(12) **United States Design Patent** (10) **Patent No.:** **US D1,033,216 S**
(45) **Date of Patent:** **** Jul. 2, 2024**

(54) **CONTAINER CAP HAVING FRUSTUM
SHAPED SIDEWALL SEGMENT ENABLING
NESTING**

(71) Applicants: **Daniel A. Zabaleta**, Cooper City, FL (US); **Dennis Stammen**, Brookville, OH (US); **Steven Todd Albright**, Piqua, OH (US)

(72) Inventors: **Daniel A. Zabaleta**, Cooper City, FL (US); **Dennis Stammen**, Brookville, OH (US); **Steven Todd Albright**, Piqua, OH (US)

(**) Term: **15 Years**

(21) Appl. No.: **29/777,334**

(22) Filed: **Apr. 5, 2021**
